ATTORNEY

UNITED STATES PATENT OFFICE.

RALPH KANAGA REX, OF CLEVELAND, OHIO.

FINGER-NAIL TRIMMER.

Application filed November 15, 1926. Serial No. 148,523.

This invention relates to finger nail trimmers, and has for its object the provision of a neat, compact and unitary structure which is capable of obtaining the best results and in which a V-shaped blade is provided at the end of a passage whereby the nail will be received in the V-shaped blade with the parts of the nail which are removed being collected and directed away from the blade by the passage.

A further object of the invention is the provision of a nail trimmer including a head having a plurality of passages transversely of the head with the passage adjacent the free end of the head being sufficiently sheared to cause the outermost passage to open at one end through the free end of the head while at the same time providing a blade having a V-shaped notch therein to receive the nail as the nail is being trimmed by the blade, the particles of the nail which are removed being collected by the passage into which the notch opens.

A still further object of the invention is the provision of a nail trimmer including a handle having at one end a nail cleaner and at its other end a nail trimmer, the trimmer being formed of a piece of metal having a transverse passage and a V-shaped notch opening through the top of the head, a blade embracing the V-shaped notch with the depth of the passage aiding in determining the extent of the cutting of the nail.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention, as expressed in the appended claims.

Figure 1 is a view in elevation of the compact unitary structure of the nail trimmer in its casing.

Figure 2 is a view in elevation of the nail trimmer partly in section and showing the oppositely disposed elements for trimming the nails.

Figure 3 is a fragmentary vertical section of the nail trimmer,

Figure 4 is a fragmentary view in perspective of the nail trimmer,

Figure 5 is another fragmentary view in perspective of the nail trimmer, and

Figure 6 is a horizontal section taken along the line 6—6 of Figure 2.

Referring more particularly to the drawings 10 designates the body or handle which has at each opposite end a longitudinal passage, as shown at 11 and 12. The portion 13 of the body is reduced in diameter and threaded as shown at 14. The portion 15 of the body is likewise reduced and threaded as shown at 16.

A hollow cap or protective casing 17 is provided with internal threads to receive the external threads 14 of the portion 13 of the body 10 and is provided with an eye 16 adapted to receive a chain for preventing loss of the nail trimmer when the same is being transported.

A nail cleaner, generally designated by the numeral 19, is adapted to project beyond the outer free end of the portion 13 of the body 10 and has a shank 20 forced into the passage 11 of the body 10 as shown at 21 between the cleaner 19 and shank 20 and 70 engages the outer free end of the portion 13 of the body and prevents further inward movement of the shank 20 in the passage. The cleaner is provided with a point 22 to facilitate the insertion of the cleaner beneath the end of the finger nail but is sufficiently rounded or blunted to prevent perforating of the skin of the operator. The inner end of the cleaner, as shown at 22, is 75 enlarged with the cleaner gradually diminishing in cross sectional area until it terminates in the point 22. As shown more particularly in Fig. 6 the cleaner in cross section presents four faces. The shank 20 as shown 80 in Fig. 3 is cemented at 24 to the side walls 85 of the passage 11 in order to aid and maintain the shank in position at one end of the body 10.

The cleaner consists of a head 25, a neck portion 26, a shoulder 27 and a shank 28 100 which is received within the passage 12 of the portion 15 of the body 10. This shank is similarly cemented in the passage 12 with the shoulder 27 abutting the outer free end of the said portion and preventing further inward movement of the shank within the passage 12. The head is formed of a solid block of metal and has a front flat face 29 and a rear flat face 30 which is of greater extent 105 than the front face. The outer end of the 110

head is sheared off at an angle as shown at 31 and is inclined upwardly from the front face 29 to the rear face 30. This head is provided with a pair of passages 32 and 33 which extend through the head and terminate at the front and rear faces of said head. The passages are normally positioned in a horizontal manner and at substantially right angles to the front and rear faces. By shearing off the outer free end 31 of the head sufficiently a V-shaped notch 34 will be provided at the periphery of which is formed a blade or trimmer 35. In order to sharpen the blade 35 it is only necessary to apply the outer end 31 of the head to a sharpening device in order to maintain the edge on the blade 35. After the blade head has been ground down sufficiently to cause the V-shaped notch to extend to the extreme rear end 36 of the head the head is then ground down until a small V-shaped notch is provided at the forward end of the passage 33, so that in effect the grinding down of the head for sharpening which eventually destroys the effect of the blade in the passage can be cured by grinding the head sufficiently to produce another V-shaped notch or cutting edge in a second passage. Any number of passages may be provided in the head as may be desired.

The member 19 is inserted beneath the nail for removing foreign matter which normally collects thereunder. The finger nail is applied to the V-shaped notch 34 and the handle is properly manipulated with sufficient pressure to cause the head to be drawn

around the nail and the blade 35 will remove portions of the nail and in a manner depending upon the manipulation of the trimmer.

I claim:—

1. A finger nail trimmer comprising a head having one end sheared off at an acute angle to the end walls of the head, said head being provided with a passage extending transversely of the head and with the end of one passage opening through the outer free end of the head, and a blade located at the periphery of the opening.

2. A finger nail trimmer comprising a body projecting from one end of the body and having a passage therethrough adjacent the free end of the head, said passage opening at one end through the free end of the head, and a blade at the periphery of the opening of the passage, said blade being V-shaped.

3. A finger nail trimmer comprising a body member having its opposite ends reduced and threaded, a hollow cap having internal threads adapted to be screwed on an end of the threaded portion of the body, a sharp pointed finger nail cleaner mounted in one end of the body member, a finger nail trimmer mounted at the opposite end of the body, said trimmer having a V-shaped slot at its outer free end and a passage extending transversely of the head and opening into the slot, and a blade embracing the slot.

RALPH KANAGA REX.
